HEAT CONSERVING SYSTEM FOR LOCOMOTIVE TERMINALS

John E. Hawe, St. Paul, Minn., and Leland G. Plant, Chicago, Ill., assignors to Railway Engineering Equipment Company, Chicago, Ill., a corporation of Illinois

Application November 19, 1930, Serial No. 496,641

4 Claims. (Cl. 122—396)

This invention relates to railway terminals of the direct steaming type, in which locomotives, employing for their normal propulsion steam generated by combustion of fuel upon the locomotive grate, are filled with water at steaming temperature and steam at propelling pressure, from a local source, so that the locomotives while at the terminal are maintained in self propelling condition without the presence of fire upon the locomotive grates; and which said terminals, for the sake of economy, have come to employ grouped apparatus and a single hot water reservoir for supplying filling water to the locomotives and feed water to the local steam generator which charges the locomotives and operates the power plant and other conveniences of the terminal.

When steam from a stationary power plant is supplied to locomotives standing in an enginehouse, to generate or maintain a working steam pressure therein without fires on the grates, a new problem arises in the economical generation of steam not encountered when stationary boilers are employed merely for supplying steam to stationary engines, pumps, etc., it being the usual power plant practice either to condense all exhaust steam from engines, pumps, etc. and use the condensate as boiler feed water, or to utilize this exhaust steam for heating fresh boiler feed water. In either case, the heat content in exhaust steam available is ample to supply or elevate the temperature of the boiler feed water to a degree considerably above the temperature of steam at atmospheric pressure.

When, however, a considerable portion of the total steam generated by the stationary boilers at a locomotive terminal is delivered to locomotives standing in an adjacent enginehouse without fires on the locomotive grates, as is the practice in direct steaming systems, then the quantity of exhaust steam available from such stationary engines, pumps, etc. as are supplied with live steam from these stationary boilers, may be insufficient in heat content to supply or elevate the stationary boiler feed water to the highest degree practical for most efficient operation; bearing in mind that this feed water must be equal in weight to the total weight of steam supplied both to the stationary engines from which exhaust is available, and to the locomotives from which there is no exhaust steam available.

In the operation of direct steaming systems, the reservoir supply of hot water essential for filling locomotive boilers with a mixture of hot water and steam which enters the boiler at or above a steaming temperature, is ordinarily heated to the

appropriate degree by the steam content of the blow-back from locomotive boilers emptied on arrival at the terminal. This blow-back is conveyed through a blowoff pipe from a connection to the locomotive in the enginehouse, to a separator in which the steam content is disengaged from the boiler water and thence conducted to a condenser of the jet type into which fresh cold water is sprayed to condense the steam. The resulting condensate and spray water heated by contact with the steam, drains from the condenser into the hot filling water reservoir where it is kept stored in readiness for use.

In steaming up locomotives, either in the manner described or with a fire on the grates, it is obvious that the higher the temperature of water with which the locomotive boiler is filled, the less fuel and time will be required for developing a desired working steam pressure on the locomotive; and if this filling water can be heated exclusively by means of blown-back steam that would otherwise be wasted, it is obvious that any increase in the temperature of filling water thus obtained represents a net fuel saving in the operation of the terminal. However, as large reservoir tanks open to atmospheric pressure are the only practical means available for storing a sufficient quantity of locomotive filling water for the operation of an ordinary terminal, it will be seen that this places a definite limitation upon the degree to which this filling water can be heated. For instance, it is found in practice that whenever the filling water thus stored in a reservoir open to atmospheric pressure, exceeds a temperature of about 200° F., it begins to vaporize and at 212° F. it will evaporate into the atmosphere as steam.

The quantity of heat available from the steam content in locomotive blow-backs varies considerably at different locomotive terminals and depends largely upon the conditions under which the terminal is operated. Thus, for instance, where it is customary practice to hold locomotives in the enginehouse at a working steam pressure for considerable periods without fires on their grates, the steam supply to locomotives from the stationary boiler plant condenses and gradually builds up the water level in the locomotive boiler so that some of this water must occasionally be blown out of the locomotive through the blow-back line. If this water is at a temperature corresponding to temperature of steam in the locomotive, it will augment the quantity of steam heat in the blow-back from locomotive boilers emptied at the terminal so that the total quan-

5 tity of steam heat in the combined blow-backs from the enginehouse may greatly exceed the amount of heat that can be utilized for raising the temperature of all the filling water required at 200° F. Where this condition applies, the logical step, and the one that is now being widely employed, is to draw the stationary boiler feed water from the same reservoir supply provided for locomotive filling water so that the 10 steam heat available from all locomotive blow-backs can be not only applied to raising the temperature of water for filling locomotive boilers, but also to heating the additional quantity of water required for feeding the stationary boilers 15 of the terminal. At terminals where a large portion of the steam from stationary boilers is delivered to locomotive boilers in the enginehouse, this practice tends to compensate for the inadequate supply of exhaust steam from engines, 20 pumps, etc. available for heating the stationary boiler feed water. For this reason, the use of a common reservoir for locomotive filling water and boiler feed water has become a quite general practice since the introduction of direct steam- 25 ing systems.

But since, as explained above, the temperature at which water can be stored in a reservoir open to atmospheric pressure is practically limited to about 200° F., and at terminals where the combined steam heat from locomotive blow-backs and engine exhaust is more than sufficient to raise all locomotive filling water and boiler feed water required to this temperature, it becomes highly desirable to avoid this very considerable 35 heat loss by providing a simple and adequate method and means for conserving all of the steam heat available, and completely utilizing it for heating both the locomotive filling water and the stationary boiler feed water to a temperature in excess of 212° F. Accordingly, the purpose of this invention is to provide a practical and adequate method and means for utilizing all the steam heat that may be available under any ordinary circumstances from locomotive blow- 40 backs and from engine exhaust, for heating both the locomotive filling water and stationary boiler feed water to a temperature substantially above that which is possible of attainment in an open hot water reservoir.

50 The aforesaid purpose is achieved by the novel combination of water heaters, exhaust steam distributing lines, water pumps, a hot water reservoir, and stationary boilers, of a locomotive terminal having steam, filling water and blow-back lines, substantially as hereinafter described.

55 The accompanying drawing shows the preferred embodiment of the invention by way of illustration.

In the said drawing, 1 represents a plurality 60 of stalls in an enginehouse, equipped for receiving locomotives 2, and connecting these locomotives up to suitable drops 3 with a blow-back line 4, a steam supply line 5 and a filling water supply line 6. Blow-back line 4 leads to a separator 7, whence the liquids escape through a pipe 8 to any desired place of disposal while the volatiles rise and flow through a pipe 9 to a condenser 10, the cold water sprays of which are supplied by pipe 11. Fresh condensing water and 65 condensate pass from condenser 10 by gravity through a pipe 12 to an elevated point in the filling water reservoir 13, which by reason of its proportions, is suitably opened to atmosphere, as, 70 for instance, through a vent 14, and in which 75 the hot fresh water is stored as a supply for

both the locomotives 2 and for a stationary steam generator 15. A plant of this nature will also include various forms of apparatus which may conveniently be driven by steam, such, for instance, as a pump 16 for feeding water from reservoir 13 to the water supply pipe 6 leading to the locomotive stalls, which pump is driven by steam engine 17; the pump 18 for forcing water from reservoir 13 through pipe 19 to the stationary steam generator 15, which pump is driven by steam engine 20; and such other convenience apparatus as may be required, typified in the present instance by the steam turbine-electric generator 21, 22.

80 Steam pipe 5, leading to the stalls 1, is supplied by the steam header 23 leading from the stationary generator 15; and this steam header will be provided with various branches through which to supply the other steam consuming apparatus, for instance, branch 24 leading to the engine 20 of the pump which supplies the stationary steam generator; branch 25 leading to the steam turbine 22 of the steam turbo-electric generator; and branch 26 leading to the steam engine 17 of the pump 16 which forces water 85 to the locomotive stalls. In order to conserve the heat exhausted from these several steam consuming apparatus for use in carrying out the present invention, a steam manifold 27 is provided with a connection 28 leading to the exhaust of the steam engine 20, a connection 29 leading to the turbine 22, and a connection 30 leading to the steam engine 17; and this steam manifold is tapped into one or more heat exchangers, here typified by the closed type water 90 heaters 31, 32, through which are passed, respectively, the filling water supplied through pipe 6 to the locomotives and the feed water supplied through pipe 19 to the stationary steam generator 15. 6a in the water heater 31, and 19a in 95 the water heater 32, typify suitable coils or other arrangement of heat transfer surfaces located in these heaters and connected in series with said pipes 6 and 19. 31a, 32a represent steam traps for the disposal of condensate accumulating in 100 the heaters 31 and 32 from the transfer of heat from the steam derived from manifold 27 to the water passing through the coils 6a and 19a.

105 In order to provide for use of steam in manifold 27 in excess of that which will be condensed 110 in the heaters 31 and 32, said manifold is provided with an outlet 33 discharging at a point 34 in the reservoir 13, sufficiently submerged to impose a head of back pressure that will cause the manifold to keep the heaters 31 and 32 filled. 115 Excess steam escaping in this way assists in keeping up the temperature of locomotive filling and boiler feed water in reservoir 13. In the event that the supply of water in reservoir 13 should be depleted to a point which will leave insufficient back pressure in pipe 33, a back pressure 120 valve 35 will maintain in said pipe 33 a resistance to escape of steam sufficient to insure the presence of steam in the heaters 31 and 32 at a pressure which will maintain the desired temperature around the water heating coil. Obviously, back pressure valve 35 may be adjusted so that it alone will control the back pressure in pipe 33, and by its regulation it may be made to vary, within limits, the pressure and corresponding temperature within the heaters.

125 We claim:

1. In a locomotive terminal, a locomotive stall having a blow-back line and a water filling line, a stationary steam generator having connections 130

through which it supplies steam to said locomotive stall, a water reservoir having connections through which, respectively, it supplies water to said filling water line and said stationary steam generator, independent heat exchangers through which, respectively, water so supplied flows to said filling water line and to said generator, an exhaust steam source, steam ducts through which exhaust steam from said source reaches said exchangers, and means permitting escape from said ducts of exhaust steam in excess of a predetermined back pressure maintained on said exhaust steam source, each heat exchanger being constructed to exchange heat from exhaust steam received by it to the water passing through it without admixture of said steam and water.

2. A locomotive terminal as described in claim 1, in which the exhaust steam source includes a plurality of exhaust steam units connected by 20 a manifold.

3. In a locomotive terminal, a locomotive stall having a locomotive boiler filling line, a filling water reservoir, a water pump drawing from said reservoir and delivering to said filling line, a heat 25 exchanger in said filling line, between said pump

and said stall, an exhaust steam pipe communicating with said exchanger, said exchanger being constructed to exchange heat from the exhaust steam received by it to the filling water passing through it without admixture of said steam and said water, an escape pipe that conducts, to the water reservoir, steam in excess of that desired for the exchanger, which is permitted to escape from the exhaust steam pipe, and means for developing back pressure in said escape pipe sufficient to maintain said desired steam pressure in the exchanger; the last-named means consisting of a hydrostatic column of water in the said water reservoir.

4. A locomotive terminal as described in claim 3, in which the last-named means consists of a hydrostatic column of water in the said water reservoir, together with a back flow valve in the said escape pipe, which said valve functions when the said hydrostatic column drops to a level insufficient to maintain the desired steam pressure in the exchanger.
